ENGINE

Carl F. Bachle, Grosse Pointe, Mich., assignor, by
mesne assignments, to Reconstruction Finance
Corporation, Detroit, Mich., a corporation of
the United States

Application September 26, 1938, Serial No. 231,711

4 Claims. (Cl. 123—90)

This invention relates to engines and more particularly to the cylinder head and associated rocker box cover assembly especially adapted for a radial air cooled aircraft engine.

More particularly, the present invention pertains to a novel assembly in which the rocker box cover is constructed and arranged for cooperative assembly with a cylinder head structure in such a way as to house the valve actuating mechanism, particularly the rocker arm, and to insure proper assembly at all times by limiting the axial displacement of the rocker arm shaft.

The present invention provides for an improved construction in which ready access may be had to the valve operating mechanism, particularly the valve rocker arm, and furthermore, provides a very compact assembly.

For a more detailed description of the present invention reference may be had to the accompanying drawing illustrating a preferred embodiment of the invention, and in which:

Fig. 1 is a fragmentary vertical sectional view of an engine illustrating the present invention.

Fig. 2 is a fragmentary vertical sectional view taken substantially on the line 2—2 of Fig. 1, and

Fig. 3 is a plan sectional view taken substantially on the line 3—3 of Fig. 2.

For purposes of illustration, the present invention is shown in conjunction with an engine of the radial air cooled type, which is usually provided with a plurality of radially extending cylinders 10 having cooling fins 11. A piston 12 is operable in said cylinder and cooperates with the cylinder head structure 13 to define a combustion chamber 14. The cylinder head structure is provided with the standard valve guides for supporting the intake and exhaust valves 15 and is further provided with an extension 16 forming the lower base portion of the rocker box, which extension also supports the usual push rods 17.

The present invention pertains particularly to the construction of the rocker box and the cover for housing the valve operating mechanism. The cylinder head extension 16 is provided with lugs or supports 18 which are provided with axially aligned drilled holes 19 for supporting a rocker arm shaft 20. The rocker arms 21 are preferably mounted between the supports 18 and are pivotally supported on said rocker arm shaft 20. Said rocker arm shaft 20 is preferably constructed of such a length as to arrange the ends thereof substantially flush with the outer faces 22 of the rocker arm supports 18 and said rocker arm shaft or pin 20 is preferably arranged to

have a snug fit within the drilled holes 19 of said rocker arm supports 18. A cover 23 is associated with the cylinder head extension and is substantially circular in plan as shown in Fig. 3 and the said cover is preferably secured to the cylinder head extension by means of a plurality of bolts 24.

In order to eliminate all chances of the rocker arm shaft or pin 19 from being displaced axially or being shifted an undue amount, the rocker box cover 23 is substantially flattened as at 25 at points substantially diametrically opposite each other (see Figs. 2 and 3). These flattened portions 25 of the rocker box cover are provided with bosses 26 which project 15 inwardly from the flattened side wall portions of the cover and are preferably formed with a flat machined face 27 which is positioned closely adjacent to the end faces of the rocker arm shaft or pin 19. It will thus be noted that there 20 is provided a very minimum clearance 28 between the ends of the pin 19 and the faces 27 of these bosses 26 and that very little movement 25 is permitted of the shaft or pin 19 relative to the supports 18 and thus it will be noted that at all times a maximum amount of bearing surface is maintained for supporting the shaft or pin 19 in said supports 18.

The present construction permits for economical manufacture of these parts since it is possible to very economically machine these parts and readily fit the same together when assembling the engine. Furthermore, the present construction facilitates maintenance of the valve operating mechanism since removal of the cover 30 which substantially houses the entire rocker arm assembly exposes this whole assembly and permits ready access to be had to said mechanism.

It will be apparent to those skilled in the art to which this invention pertains that various 40 modifications and changes may be made therein without departing from the spirit of the invention or from the scope of the appended claims.

I claim:

1. An engine structure having in combination, 45 a cylinder head, valve means supported by said cylinder head, valve actuating mechanism including a valve actuating rocker arm, rocker arm supports carried by said cylinder head and projecting outwardly beyond the outer end of said 50 cylinder head, a pin supported by said rocker arm supports and pivotally supporting said rocker arm, and a rocker box cover secured to said cylinder head and housing said rocker arm supports, said rocker box cover having inwardly 55

- projecting bosses axially aligned with said pin and positioned closely adjacent to the end faces of said pin for limiting axial movement of said pin.
2. An engine structure having in combination, 5 a cylinder head, valve means supported by said cylinder head, valve actuating mechanism including a valve actuating rocker arm, rocker arm supports carried by said cylinder head and projecting outwardly beyond the outer end of said cylinder head, a pin supported by said rocker arm supports and pivotally supporting said rocker arm, and a rocker box cover secured to said cylinder head and housing said rocker arm supports, said rocker box cover constructed substantially circular in plan and having inwardly projecting bosses axially aligned with said pin and positioned closely adjacent to the end faces of said pin for limiting axial movement of said pin.
3. An engine structure having in combination, 10 a cylinder head, valve means supported by said cylinder head, valve actuating mechanism including a valve actuating rocker arm, rocker arm supports carried by said cylinder head and projecting outwardly beyond the outer end of said cylinder head, a pin supported by said rocker arm supports and pivotally supporting said rocker arm, and a rocker box cover secured to said cylinder head and housing said rocker arm supports,
- 15
- 20
- 25

said rocker box cover constructed substantially circular in plan and having a pair of bosses projecting inwardly from substantially diametrically opposite portions of the side wall of said cover, said bosses being axially aligned with said pin and positioned closely adjacent to the end faces of said pin for limiting axial movement of said pin.

4. An engine structure having in combination, 10 a cylinder head, valve means supported by said cylinder head, valve actuating mechanism including a valve actuating rocker arm, rocker arm supports carried by said cylinder head and projecting outwardly beyond the outer end of said cylinder head, a pin supported by said rocker arm supports and pivotally supporting said rocker arm, and a rocker box cover secured to said cylinder head and housing said rocker arm supports, said rocker box cover constructed substantially circular in plan and having a pair of bosses projecting inwardly from substantially diametrically opposite portions of the rocker box cover side wall, said bosses each having an inner flat face substantially axially aligned with said pin, the faces of said bosses being located closely adjacent to the end faces of said pin for limiting axial movement of said pin.

CARL F. BACHLE.
